[57] CLAIM

The ornamental design for an in-circuit emulator, as described and shown.

DESCRIPTION

FIG. 1 is a front view of the illustrated embodiment of the in-circuit emulator;

FIG. 2 is a back view of the in-circuit emulator of FIG. 1;

FIG. 3 is a left side view of the in-circuit emulator of FIG. 1;

FIG. 4 is a right side view of the in-circuit emulator of FIG. 1;

FIG. 5 is a top view of the in-circuit emulator of FIG. 1;

FIG. 6 is a bottom view of the in-circuit emulator of FIG. 1;

FIG. 7 is an isometric bottom view of the in-circuit emulator of FIG. 1; and,

FIG. 8 is an isometric top view of the in-circuit emulator of FIG. 1.
